UNITED STATES PATENT OFFICE.

EDWARD HAUSER, OF NEW YORK, N. Y.

CUTLERY IMPLEMENT.

Application filed October 3, 1924. Serial No. 741,470.

To all whom it may concern:

Be it known that I, EDWARD HAUSER, a citizen of the United States, residing at New York city, in the county of New York and State of New York, have invented new and useful Improvements in Cutlery Implements, of which the following is a specification.

This invention has reference to cutlery implements and more particularly to that class thereunder known as corn cob forks.

The primary object of the invention resides in the provision of a device of the above stated character primarily designed and constructed to facilitate the eating of corn on the cob more properly, at the dinner table, and thus obviate the necessity of holding such with the fingers; and furthermore eliminates the soiling or burning of the fingers.

To this end, use is made of a fork of the capacity above indicated and one so constructed to permit of the turning of the cob of corn and to hold the latter at various angles for convenience of the person eating to obtain therefrom the complete contents of such.

A further object of the invention aims in providing a fork provided with an improved constructed handle designed for rendering convenience to the user in holding the cob of corn when relishing such and further to prevent the finger tips from coming in contact with the hot corn.

With these and other objects in view, the invention resides in certain novel features of construction and combination of parts, the essential features of which are herein-after fully described and particularly pointed out in the appended claims, and are illustrated in the accompanying drawing, in which:—

Figure 1 is an elevation illustrating the device in use.

Figure 2 is a perspective view of one of the forks.

Figure 3 is a view partly shown in section.

Figures 4 and 5 are elevational views illustrating slight modified forms of forks.

Figure 6 is an end elevation of Figure 5.

Figure 7 is an elevational view illustrating a further modified form of fork.

Referring more particularly to the accompanying drawing, wherein like charac-

ters of reference denote several parts throughout the specification, the fork generally is denoted by the character 5 and comprises a handle 6 and a head 7. This handle member 6 is primarily designed for convenience of the user in holding such between the thumb and index finger, if desired, and is provided adjacent the head 7 thereof with a concaved portion 8. The extremity of the head 7 is provided with an outwardly flared guard 9, the purpose of which will be clearly defined as the description of the invention is proceeded with.

Reference being had more particularly to Figures 1 to 3 inclusive of the drawings, use is made of a supporting member 10 comprising a main penetrating tang 11 and a pair of auxiliary penetrating tang members 12. The auxiliary tang members are arranged at opposite sides of the main tang member. The purpose of so constructing and arranging the auxiliary tang members with respect to the main tang member, is to facilitate the auxiliary tang members penetrating the ends of the corn cob 13, better shown in Figure 1 of the drawing, and by so doing serve to prevent any accidental rotation of the corn cob 13 after the main penetrating tang member 11 is forced into the end of the cob. However, I desire to provide means to enable the user in holding the corn cob at various angles for convenience in relishing such, and to this end a universal connection denoted broadly by the character 14 is employed. This universal connection 14 includes a resilient female member 15 provided integrally with the supporting member 10 and on the rear end thereof and this female member receives the male member 16 provided on the stem 17. The stem 17 passes through a centrally located opening 18 provided in the threaded stem 19 of the guard member 9 and is fastened therein by the provision of any suitable fastening means, such as a nut or the like. It will therefore be manifest that by providing the guard 9 with the concaved socket 20, establishes a loose connection between the fork and the handle and thereby allows the supporting member to freely move at various angles with respect to the corn cob when desiring to relish corn on the cob in dining rooms and other public places. Again, the guard member 9 pre-

vents the fingers of the user from engaging the hot corn when the device is in use.

Reference now being had to the modified form of fork member illustrated in Figure 4 of the drawing, a pair of main penetrating tang members 11' are employed instead of a single penetrating tang member, and to opposite sides of the main penetrating tang members, I provide the usual auxiliary penetrating tang members and for the sake of clearness are denoted by the character 12'. The modified form of fork member illustrated in Figure 5, provides a main penetrating tang member 11² and formed integral with this main penetrating tang member, and to opposite sides thereof, is provided a substantially semi-elliptical construction of auxiliary penetrating tang members and here indicated by the character 12².

The still further modified form of supporting member illustrated in Figure 7 includes a main penetrating tang member 11³ having formed integral therewith and to opposite sides of the extremity thereof, a pair of auxiliary penetrating tang members 12³.

I have entered into a detailed description of the construction and relative arrangement of the parts embraced in the present and preferred embodiment of my invention in order to impart a full and exact understanding of the said embodiment. I do not desire, however, to be understood as confining myself to the specific construction and relative arrangement of parts inasmuch as in the future practice of the invention there are changes and further modifications may be made such as fall within the scope of my invention and as defined in my appended claims.

What is claimed as new is:—

1. A cutlery implement embodying a handle, a supporting member carried by said handle, said supporting member comprising a main penetrating member adapted to penetrate the end of a corn cob and a pair of auxiliary penetrating members, the said auxiliary penetrating members adapted to prevent accidental movement of the corn cob with respect to said implement, and

means for angularly adjusting said handle with respect to said supporting member.

2. A cutlery implement embodying a handle, a supporting member carried by said handle, said supporting member comprising a main penetrating member adapted to penetrate the end of a corn cob and a pair of auxiliary penetrating members arranged to opposite sides of the main penetrating member, the said auxiliary penetrating members adapted to prevent accidental movement of the corn cob with respect to said implement, and means for angularly adjusting said handle with respect to said supporting member.

3. A cutlery implement embodying a handle having a head terminating with a guard, a supporting member carried by said head, means for universally adjusting said handle with relation to said supporting member, said supporting member comprising a main penetrating member adapted to penetrate the end of a corn cob and a pair of auxiliary penetrating members, said auxiliary penetrating members adapted to prevent accidental movement of the corn cob with respect to the implement.

4. A cutlery implement embodying a handle, a head detachably connected to one end of the handle and provided with an outwardly flared guard, means for universally adjusting said handle with relation to said supporting member, a supporting member associated with said head, said supporting member comprising a main penetrating member, and a pair of auxiliary penetrating members the said auxiliary penetrating members adapted to prevent accidental movement of the corn cob with respect to the implement.

5. A cutlery implement of the character set forth including a handle, a supporting member adjustably associated with one end of the handle and adapted to penetrate the end of a corn cob, the said supporting member when in supporting position enables the handle to be moved at various angles for convenience of the user.

In testimony whereof I have affixed my signature.

EDWARD HAUSER.
